WIRE HANDLING HAND TOOL
Joseph A. Tramontana, 1736 Central Ave.,
Alameda, Calif.
Filed Nov. 6, 1961, Ser. No. 150,223
7 Claims. (Cl. 81—5.1)

This invention relates to a small hand tool for handling strand-like material such as wrapped wire cables.

In manually handling wrapped wire cables for extended periods of time considerable wear and tear on a person's hands is normally experienced. The problem is aggravated in those applications wherein the strands must move through the hand, for example, as where one end of a strand is made fast, while the other end is free to pay out from a supply reel or the like.

Such an application, for example, is to be found in making cross connections in central offices of telephone systems. There, a reel of two-lead or "paired" wire supplies leads to be first connected to terminals at a location on one side of the office or station. A bight of wire is then grasped and payed out as a workman proceeds to the terminals at another location to be connected by the same two-conductor wire. In a number of instances it is not unusual to find that two paired wires, one a "transmit" wire and the other a "receive" wire, will have to be connected between the same two locations. A supply reel is usually provided for each.

The most efficient approach to making such a dual connection between the same two locations has been considered to be to pay out both strands of paired wire at the same time. However, since the two locations to be connected are sometimes somewhat remote from each other, it is sometimes difficult to identify which wire is which from a position at the second location to be connected. The problem of identifying which wire is associated with which particular supply reel could of course be solved by color coding of the wrapping on the wires, but this has been considered to be too expensive for some applications.

Accordingly, it is an object of the present invention to provide a hand tool which saves wear and tear on a workman's hands while paying out a bight of a flexible strand, and which also serves to isolate and identify a pair of such strands with respect to each other.

It is another object of the invention to provide a hand tool for more easily handling flexible wire strand material.

Other objects of the invention will be pointed out in the following description and claims and illustrated in the accompanying drawing, which discloses, by way of example, the principle of the invention and the best mode which has been contemplated for applying that principle.

In the drawings:

FIGURE 1 shows in perspective view a preferred embodiment of the invention; and

FIGURE 2 shows a modification of the invention shown in FIGURE 1.

The invention includes a pair of members 1 and 2 coupled together in scissor-like fashion by a pin 3. Each of members 1 and 2 is provided with a grip portion 1a and 2a respectively. Member 1 is provided with a flat broad jaw portion 5, while member 2 includes a pair of grooved sheaves 7 mounted for rotation upon an axle 8. Member 2 includes a U-shaped jaw portion 9, the arms of portion 9 being designated 9a. Axle 8 is mounted between arms 9a and fastened therein by a cotter pin 11, while sheaves 7 are spaced from arms 9a as well as from each other by washers 12. Stamped upon the face portion of U member 9 are the two initials "R" and

"T" so that each is associated with one of grooved sheaves 7.

Referring to the drawing, one suitable application for the invention is shown wherein a paired wire 15 and a paired wire 16 are made fast at their ends 15a and 16a respectively. Wire 15 has been arbitrarily designated a "transmit" wire while wire 16 is designated a "receive" wire so that the stamped initials on the face of member 9, as well as the physical association of sheaves 7 with wires 15 and 16, serve to identify the transmit and receive wires. Wires 15 and 16 are fed from supply reels 18 and 19 respectively, located at a location remote from the terminals to be connected.

As the invention would be used, connections 15a and 16a are first made, wire 15 being led over the groove of the "T" sheave 7, while wire 16 is led over the "R" sheave. As thus arranged, squeezing grip portions 1a and 2a together lock a bight of wires 15 and 16 over their respective sheaves 7. It should be noted that sheaves 7 will not touch jaw portion 5 when jaw portion 5 is closed upon jaw portion 9. Therefore, with wires of diameters smaller than the depth of the grooves in sheaves 7, the bight of each of wires 15 and 16 can be readily payed out from their reels while maintaining them separate and identified.

Therefore, it is readily apparent that a workman using this hand tool will be saved considerable wear upon his hands while efficiently and expeditiously handling flexible wire-like strands.

Referring to FIGURE 2, there is shown a modification of the broad jaw portion 5 which in practice has tended to minimize snagging when twisted wire cables are being handled. As shown, jaw portion 5' has been formed generally to conform to the cylindrical shape of sheaves 7. The distal end of the forwardmost arm 9a of FIGURE 1 has been provided with a cylindrically shaped surface 14 which fits into the inner curvature of jaw portion 5'. With the above modification, jaw portion 5' is retained substantially uniformly spaced from the edges of sheaves 7 throughout a substantial portion of their circumference.

I claim:

1. A wire handling hand tool comprising a pair of jaw members pivoted to close upon each other to an abutting face to face relation, an axle carried in that face of one of said jaw members which opposes the face of the other jaw member, a grooved sheave mounted for rotation on said axle, said other jaw member overlying said sheave, said sheave being spaced from said other jaw member and free to rotate when said jaw members are closed to said relation, whereby a flexible wire can be fed over the groove of said sheave while retained therein by closure of the other said jaw member thereacross.
2. A wire handling hand tool comprising a pair of jaw members pivoted to close upon each other to an abutting face to face relation, an axle carried in that face of one of said jaw members which opposes the face of the other jaw member, at least a pair of grooved sheaves mounted for rotation on said axle, said other jaw member overlying said sheaves, said sheaves being free to rotate when said jaw members are closed to said relation, whereby a pair of flexible wires can be fed over the grooves of said sheaves while retained therein by closure of the other said jaw member thereacross.
3. A wire handling hand tool comprising a first and second member, each of said members terminating in a jaw portion disposed in opposed relation, said members being coupled scissor-like intermediate their ends and disposed to permit said jaw portions to close upon each other in abutting relation, one of said jaw portions including an axle extending substantially parallel to the

70

axis of said jaw portion and disposed within an opening in the abutting face thereof, a pair of grooved sheaves mounted for rotation on said axle, the other said jaw portion overlying said sheaves, said sheaves being sufficiently spaced from the other said jaw portion when said jaw portions are in abutment whereby a pair of flexible wire-like strands can be maintained associated with said sheaves respectively while passing freely thereover substantially transversely of said jaw portions.

4. The invention according to claim 3 wherein said sheaves are mounted for independent rotation.

5. A wire handling hand tool comprising a first and second elongate member, each of said members including a jaw portion, the jaw portion of said first member having an overhanging lip adapted to contact the jaw portion of said second member, said members being coupled together intermediate their ends by pivot means whereby urging said members together at one end closes said jaw portions upon each other in abutting relation, an axle supported by the jaw portion of said first member, said axle extending in a plane substantially parallel to the axis of said jaw portion and through said overhanging lip and being spaced from the jaw portion of said second member when said jaw portions are in abutting relation, at least one grooved sheave rotatably mounted on said axle, said sheave being disposed to permit rotation when said jaw portions are closed to abut each other, the jaw portion of said second member being spaced from said sheave by the overhanging lip of the jaw portion of said first member and shaped in substantially conforming relation to said sheave axially thereof, whereby a flexible strand can be fed over the groove of said sheave while enclosed therein by closure of the jaw portions of said second member thereacross.

10

25

6. A hand tool as defined in claim 5 wherein the jaw portion of said first member is generally U-shaped.

7. A hand tool for pulling a bight of wrapped flexible wire from each of a pair of storage reels comprising a first jaw member, a second jaw member pivoted to close scissor-like upon said first jaw member, said first jaw member including at least a pair of grooved sheaves mounted to rotate in a plane transverse to the axis of said first jaw member and disposed in that face of the first jaw member which opposes the second jaw member, a portion of said second jaw member extending across the edges of said sheaves and having a transverse curvature along a portion of its length in substantially conforming relation to the edges of said sheaves, said first jaw member being disposed to abut said second jaw member and to maintain a fixed spaced relation between said second jaw member and the edges of said sheaves to permit a wrapped wire to be passed between each of said sheaves and said second jaw member when said jaw members are closed in abutting relation upon each other, whereby a bight of wire can be pulled from each of a pair of associated storage reels simultaneously over both said sheaves.
